UNITED STATES PATENT OFFICE.

FREDERIC C. MORTON, OF CAMBRIDGE, MASSACHUSETTS.

DESIGN FOR A VEHICLE BODY AND TOP.

SPECIFICATION forming part of Design No. 32,627, dated May 1, 1900.

Application filed April 2, 1900. Serial No. 11,264. Term of patent 14 years.

To all whom it may concern:

Be it known that I, FREDERIC C. MORTON, a citizen of the United States, residing in Cambridge, in the county of Middlesex and State of Massachusetts, have invented and produced a new and original Design for a Vehicle Body and Top, of which the following description, in connection with the accompanying drawings, is a specification, like letters on the drawings representing like parts.

The design relates to a vehicle-body and top therefor; and it consists in a vehicle body and top distinguished by their peculiar shape, as will be hereinafter set forth and claimed.

Figure 1 is a side elevation of a vehicle body and top embodying this design, and Fig. 2 a plan view of the vehicle body and top shown in Fig. 1.

The leading and distinguishing feature of this invention consists in a vehicle body and top of the shape or configuration shown, and consists in a substantially rectangular-shaped box or top *a*, set upon the rear portion of the body *b* of the vehicle and diagonally with relation thereto. 20 25

I claim—

The design for a vehicle body and top substantially as herein shown and described.

In testimony whereof I have signed my name to this specification in the presence of two subscribing witnesses. 30

FREDERIC C. MORTON.

Witnesses:

JAS. H. CHURCHILL,
J. MURPHY.
